UNITED STATES PATENT OFFICE.

ROBERT EDDY, OF MILWAUKEE, WISCONSIN.

DESIGN FOR A RUBBER BALL.

51,722.

Specification for Design.

Patented Feb. 5, 1918.

Application filed November 12, 1914. Serial No. 871,799. Term of patent 14 years.

To all whom it may concern:

Be it known that I, ROBERT EDDY, a citizen of the United States, residing at Milwaukee, in the county of Milwaukee and State of Wisconsin, have invented a new, original, and ornamental Design for a Rubber Ball, of which the following is a specification, reference being had to the accompany drawings, forming part hereof.

The figure is a view in elevation of a rubber ball showing my improved design.

I claim:—

The ornamental design for a rubber ball, as described and shown.

ROBERT EDDY.
